(57)

CLAIM

The ornamental design for a cantilevered eating utensil assembly, as shown and described.

DESCRIPTION

FIG. 1 is a top assembled view thereof;
FIG. 2 is a top disassembled view thereof;
FIG. 3 is a bottom assembled view thereof;
FIG. 4 is a bottom disassembled view thereof;
FIG. 5 is a left side assembled view thereof; and,
FIG. 6 is a right side assembled view thereof.
The broken lines shown illustrate environmental structure and form no part of the claimed design.

1 Claim, 5 Drawing Sheets
